Joseph Turner, Poland, Maine

Letters Patent

The Schedule referred to in these Letters Patent and making part of the same containing a description in the words of the said Joseph Turner himself of his improvement in a machine for churning butter. —

Know all men by these presents. Be it known that Joseph Turner of Poland in the County of Cumberland and state of Maine has invented a new and useful improvement in a machine for churning butter from milk & cream. & that the following is a full and exact description of the construction and operation and operation of the said machine as is visible and impressed by me. The machine is constructed of hard wood in the following manner. Two pieces of wood two feet & eight inches long and from one to one and a half inches in thickness and from three to three and a half inches in depth and grace -nated towards the ends from one to one and a half inches at each end by that part of the arranged churning shafted A from the two sides of the foundation of the machine. The cross pieces of the same dimensions of the side pieces above described for the churning are inserted by means of a Mortise and tenon each at an equal distance from the side pieces and at such a distance from each other as may be convenient. On each extremity of the side pieces there are inserted by means of a tenon and Mortise four posts one foot high exclusive of tenon and from one to one and a half inch in thickness and from two to two and a half inches in width as by letter (B) will appear. The shafts from eighteen to twenty inches in length and from one and a half to two inches square are inserted in the top of the before described posts so as to revolve on guides, one from an inch to an inch and a half in diameter. These shafts project beyond the posts one inch four inches and are let into them planed in the posts by means of a Mortise and secured

by a shoulder & key. On the projecting end of the left post there are mortises of a tenon and a mortise two and a half inches long exclusive of Mortise one inch and a half square. There are when the machine is not in motion just parallel with the end posts. In the ends of each of these are mortises three fourths of an inch in width into which there is inserted a bar of the same thickness of the Mortise & an inch and a half wide connecting the two arms and forming joint. A wood or iron pin fastens the bar of the bar to the extremity of the arms as will appear by the letter C. Another bar exactly over the one described is immovably fixed to the two posts parallel with the other when the machine is stationary, through which there is a mortise two inches wide & six long as by letter (E). A lever from three to four feet long and two inches square is then connected with the moveable bar by means of Mortise in said bar fastened by a wood or iron pin so as form a joint and being inserted through the immovable bar is then fastened by a wood or iron pin also. This last forms the fulcrum as will be seen at letter (F) & handle from four to six feet long is attached by means of a joint to the upper end of the lever as per letter (G). In the left half way between the posts are inserted two long iron stay bars immovably so as nearly to meet. These arms are two inches square and near the ends are inserted by means of a Mortise in the same two Connectors or links the upper part of which is formed by a tenon and the lower part by a Mortise. These are connected to the arms by means of a pin and forms a joint and are about four inches in length including the tenon and Mortise as will appear by the letter (H). To the lower part of this link or connector is attached the staff of the chain dash or pump rod which are alike. The chain to which the above machinery is applied is constructed as follows. A box one foot square and from eighteen inches to the feet in height constitutes the Churn. This is made of pine plank or board one inch and a quarter thick halved together at the corners. This stands on a plank bottom projecting

two inches in all directions two inches thick. The sides of the Churn are formed of a half of two pieces of wood two inches in length put together in the form of a cross and called when finished a half dasher. From each side of these half dashers there projects towards the front two one inch square blocks which run in two grooves on each side of the Churn three eights of an inch deep. The Churn is covered by a lid and set into the sides three eights of an inch and through it there are made holes sufficiently large for the staffs of the dasher to pass in their movements, up and down. The length of the dash depends upon the size of the Churn. The machine is placed upon the Churn and the space in the clear between the side pieces and the top pieces is calculated to be just the size of the Churn and is supported by means of blocks on each side of the Churn. This machine may be fastened to the Churn by means of hasps if it is found necessary. The wheel is put in motion by revolving the lower part of the handle of Churn as my invention the formation of the dasher, and the manner of their running, in grooves, and all the power ^{now} applied to the above described machine, and all the work consisting the arms with the staffs of the dasher, which admits the dasher to stay in the grooves and further the double lever power by means of the immovable ten-
